UNITED STATES PATENT OFFICE.

SAMUEL T. SMITH, OF LOS ANGELES, CALIFORNIA.

PIPE TONGS.

Application filed November 19, 1925. Serial No. 70,011.

My invention relates to pipe wrenches and tongs, and it consists in unique tongs which are very useful in the oil-well industry.

5 Tongs are employed around an oil well for making and breaking joints of drill pipe and pump tubing and sometimes weigh as much as 850 pounds. Such tongs are usually supported by a three-point suspension 10 directly adjacent to the center of the derrick and are swung into engagement with one of the parts to be connected or disconnected. The tongs by reason of the manner in which they are supported do not remain in a horizontal plane when swung but tilt and therefore do not engage the part absolutely correctly.

It is an object of this invention to provide 20 tongs and supporting means which permit the tongs to be swung in a horizontal position into and out of engaging position but prevent any side twisting or tilting of the tongs.

Large tongs cannot be loosened when there 25 is any tension thereon, and are so heavy that two men are required to operate them. When tongs are to be loosened the tension must first be removed therefrom and the jaws must be opened. This requires the attention of the draw-works man as well as two tong men.

It is also an object of this invention to 35 provide tongs which may be loosened with a tension thereon and require only one man for the operation thereof.

It is another object of this invention to provide tongs having means for locking said 40 jaw in open or closed position.

It is another object of this invention to 45 provide tongs having a novel form of jaw loosening arrangement which may be operated by one man.

It is a further object of the invention to 50 provide tongs in which the jaws thereof when not in use are held in open position ready to receive a pipe.

It is another object of the invention to 55 provide tongs in which the parts are so arranged that the strains on the jaws and connecting parts are all in a longitudinal direction and not in a lateral or cross direction.

Other objects and advantages of the invention will be made evident hereinafter.

Referring to the drawings in which I illustrate 60 a preferred embodiment of my invention:

Fig. 1 is a view of the head of my tongs showing the jaws in open position ready to receive a pipe.

Fig. 2 is a view of the tongs showing the 65 pipe in engagement with a free jaw of my invention,

Fig. 3 is a view showing the jaws in locked position around the pipe and the manner in which the locking is accomplished,

Fig. 4 is an enlarged partially sectioned view showing the jaws in clamping position,

Fig. 5 is a section taken on the line 5—5 of Fig. 4, and

Fig. 6 is a section taken on the line 6—6 70 of Fig. 4.

Referring to the drawings, a preferred form of my invention consists of a handle 11 having a main jaw 12 formed integrally at one end thereof. The main jaw 12 has an arcuate engaging portion 13. An insert member 15 is carried by the main jaw 12, having teeth 16 which project inwardly from the arcuate engaging face 13.

At one side of the engaging face 13 and backwards therefrom there extends through the jaw 12 a pivot 17 which carries at the opposite ends thereof and to each side of the jaw 12, free jaw links 18. The other ends of the free jaw links 18 extend on opposite sides of a tongue 19 of a free jaw 20 and are secured thereto by a pivot 21, the free jaw links 18 resting near opposite ends of the pivot 21. The free jaw 20 is provided with an internal arcuate engaging face 23. Secured on opposite sides of the free jaw 20 are engagement plates 24. These engagement plates 24 have openings 25 through which the pivots 21 extend and are further provided with openings 27 through which screws 28 extend for securing the engagement plates 24 tightly to the free jaw 20. The engagement plates 24 have internal arcuate faces 29 which are formed on the same radius as the engagement faces 13 and 23. An opening spring 30 is carried on the ends of the pivots 17 and 21 and by one of the screws 28. This opening spring is provided for the purpose of resiliently holding the free jaw 20 in open position, such as 95 shown in Fig. 1 of the drawings.

Directly in back of the engagement face 13 of the jaw 12 there is carried a main pivot 32, the opposite ends of which extend through link portions 34 of a latch jaw support 35, this pivot 32 serving to hingedly 110 secure the latch jaw support 35 to the main

jaw 12. The extending ends of the link portions 34 pass on each side of an inner end of a latch jaw 37 and are pivoted thereto by a pivot 38 which extends therethrough and extends through the latch jaw 37. The link portions 34 have arcuate faces 39 and the latch jaw 37 has an arcuate face 38a.

Extending from the inner ends of the link portions 34 is an arm 41. This arm 41, as shown in Figs. 4 and 5, extends between the free jaw links 18 and has a clevis 42 formed at the outer end thereof. A jaw-clamping spring 44 is compressed between a face 45 of the main jaw 12 and an adjacent face 46 of the arm 41, this spring being retained in place by pins 47 and 48 of the main jaw 12 and the arm 41 respectively. A link 50 is pivoted to the clevis 42 by a pin 51 and is pivoted by a pin 52 to a lever 53, this lever 53 being pivotally secured at 55 to one end of the main jaw 12. The lever 53 is L-shaped, as shown, so that a portion 57 thereof extends forwardly in a position to be easily manipulated by hand.

Extending from the main jaw 12 is a strop 60 having an inner face 61 and a side face 62. Formed on the latch jaw 37 is a projection 64 having an inner face 65 and an outer face 66. When the latch jaw is in open position, as shown in Fig. 1, the inner face 61 of the strop 60 is in engagement with the outer face 66 of the projection 64, thus holding the latch jaw in this position. The faces 61 and 66 are held in pressural engagement by the spring 44. This spring 44 tends to swing the arm portion 41 of the latch jaw support 35 forwardly, which results in a tendency to swing the link portions of the latch jaw support rearwardly. Since the latch jaw is carried at the extending ends thereof, it is moved rearwardly so that the outer face 66 of the projection 64 pressurably engages the inner face 61 of the strop 60. This pressure of engagement between the faces 61 and 66 may be released by swinging the lever 53 from the position shown in Fig. 2 into the position shown in Fig. 3. This swinging of the lever results in swinging the latch-jaw supporting member 35 against the action of the spring 44 in a manner to draw the arm 41 rearwardly and move the link portions 34 of the latch-jaw support forwardly, thus releasing the engagement between the two mentioned faces.

A latch-jaw closing spring 70 is extended around one end of the main pivot 32 and one end of the pivot 38. The extending end of the spring 70 is provided with a hook portion 71 which extends around the latch jaw 37, as shown, so that when the latch jaw is released the spring will swing the latch jaw into closed position, as shown in Fig. 3 and Fig. 4.

The latch jaw is provided with a latch lug 73 having an inner face 74 which engages a

latching face 75 of the free jaw 20. Thus when both of the jaws are in closed position, the free ends thereof will be locked together.

When the lever 53 is released from the position shown in Fig. 3, it will move into the position shown in Fig. 4 and the parts of the tongs will occupy the positions shown in this figure. The stop 60 swings inwardly until the inner face 61 thereof moves adjacent to a face 65 of the latch jaw 37 and so that the outer face 62 of the stop 60 moves into a position adjacent to the inner face 65 of the projection 64. When in this position the latch jaw 37 is locked in closed position, since it cannot swing outwardly.

A complete operation of my invention is substantially as follows:

In Fig. 1 the different parts of my invention are shown in their open position, 77 denoting a pipe which is being extended into position to be clamped. This pipe 77 engages the engagement plates 29 and thus swings the free jaw 20 against the action of the opening spring 30 from open position into closed position, as shown in Fig. 2. The arcuate faces 29 of the engagement plates 24 and the face 23 of the free jaw 20 are in engagement with the pipe 77. After the parts have been moved into the position shown in Fig. 2, the lever 53 is manually moved from the position shown in Fig. 2 into the position shown in Fig. 3. When the lever is swung, the link 50 pulls upon the extending end of the arm 41, thus pivoting the latch-jaw supporting member in a manner to swing the link portions thereof forward. This results in a disengagement between the inner face 61 of the stop 60 and the outer face 66 of the latch jaw 37. When this disengagement occurs the closing spring 70 operates to swing the latch jaw into closed position. The latch jaw is shown in closed position in Fig. 3.

Referring to Fig. 4, the latch lug 73 drops into engagement with the latch face 75 of the free jaw 20, thus locking the free ends of the free jaw and the latch jaw together. After the latch jaw has been allowed to move into closed position the lever 53 is released and the parts are moved into the positions shown in Fig. 4 by the action of the spring 44 forcing forwardly on the arm 41 of the latch jaw support 35. This action results in the link portions 34 swinging rearwardly and moving the parts so that the projection 64 of the latch jaw 37 extends to one side of the stop 60 and so that the face 65 thereof is in engagement with the face 62 of the stop. The action of the spring between the main jaw 12 and the arm 41 tends to pivot the main jaw 12 on the main pivot 32. This tends to bring the engagement face 13 into engagement with the pipe 77 and to contact the teeth 16 with the pipe. Also the tendency is to pull upon the free jaw 20 through

the free jaw link 18. This action, therefore, results in a resilient clamping of the main jaw, the free jaw, and the latch jaw in contact with the pipe 77.

6 The tongs are then operated by pulling on the handle 11 in a direction indicated by the arrow 79. This pivots the main jaw 12 and tightens the other two jaws against the pipe 77, for forcing the teeth 16 into the pipe 77. 10 until the inner face 61 of the stop 60 engages the face 75 of the latch jaw 37. When this position has been reached the teeth 16 cannot embed any farther in the pipe 77.

The three jaws are so arranged that they 15 exert an even pressure upon all portions of the pipe 77 and will not, therefore, tend to flatten the pipe. All of the parts except the handle of the tongs are designed so that the strains thereupon are in a longitudinal direction and not in a lateral or transverse direction, this permitting a light construction of 20 the tongs without breakage.

When the tongs are to be removed from the pipe 77, the lever 53 is engaged and 25 again swung into the position shown in Fig. 3. The latch jaw 37 is unlocked and may be then swung into open position as shown in Fig. 2, this being easily accomplished by means of a handle 80 which extends therefrom. When the latch jaw has been swung 30 into open position the lever 53 is released and the parts moved into such positions that the stop 60 engages the projection 64 as previously described, thus again locking the latch jaw 37 in open position. The tongs are then drawn from the pipe 77, and the parts will again assume the positions shown 35 in Fig. 1 ready for the reception of another pipe.

40 A further feature of my invention resides in the manner in which the tongs are supported. Referring particularly to Figs. 4 and 6 an opening 85 is provided through the handle 11 directly adjacent to the main jaw 12, this opening being elongated in the direction of the extension of the handle 11. Extending from opposite sides of the handle 11 and around the forward end of the slot 85 are cuff or channel formations 86. These 45 channel formations 86 surround the forward part and part of the sides of the opening 85. The channel formations 86 co-operate to provide a channel 87 through the handle of the tongs. Extending through this channel 50 87 is a supporting rod 88 which may be secured in its upper end, not shown, in any suitable manner. The lower end of the supporting rod 88 is provided with a hook 89 which extends around the bottom of the 55 lower channel portion 86, thus providing means for supporting the tongs. The channel 87 is of a width very close to the diameter of the supporting rod 88; therefore, any side tipping of the tongs is prevented. Further, 60 the tongs are prevented from being moved 65

backwards from a position shown in the drawings by engagement of the bottom of the channel with the supporting rod 88. However, the tongs may be moved forwardly 70 into position to engage the pipe, and when this occurs the supporting rod 88 will occupy a position indicated by dotted lines 90 of Fig. 6. One very important part of this manner of suspension is that the tongs may be moved forwardly into engagement with a 75 pipe in a horizontal plane. This is principally because I provide a single suspension for the tongs and this is possible by the novel arrangement of the channel formation 86 and the construction of the supporting rod 80 88. These constructions cooperate to prevent the tongs from being moved in any direction except into position for engagement with a pipe. When the tongs are in a position for engagement with the pipe they may 85 be retracted into the position shown in Fig. 6, but cannot be moved outwardly beyond this position. The tongs are supported in such a place that they are substantially in balance. The supporting means is also such 90 that the tongs may be turned over and used in inverted position.

From the foregoing description it is evident that my invention resides in a novel form of tongs having three jaws adapted to engage a pipe with equal pressures. The free jaw is resiliently retained in open position, but may be moved into closed position when the engagement plates are engaged by a pipe. This construction eliminates a man 100 for closing the jaw. Also of importance is the means for locking the latch jaw in open or closed position and the means for swinging the latch jaw into closed position when it is released. The latch jaw support 35, its 105 operating mechanism, and the spring 44 are also important parts of my invention. Another feature resides in the supporting of the tongs, which makes the handling of the 110 tongs very simple.

I claim as my invention:

1. In tongs, the combination of a handle, a main jaw rigidly provided upon an end of said handle, a free jaw, link means connecting said free jaw to said main jaw, a latch jaw, a latch-jaw support for connecting said latch jaw to said main jaw, and latching means whereby said latch jaw is latched to said free jaw when said jaws are in closed 115 position.

2. In tongs, the combination of a handle, a main jaw provided upon an end of said handle, a free jaw, said free jaw being independently movable, a link means connecting said free jaw to said main jaw, a latch jaw, a latch-jaw support for connecting said 120 latch jaw to said main jaw, latching means whereby said latch jaw is latched to said free jaw when said jaws are in closed position, and resilient means for holding said 125 130

free jaw in open position independently of said latch jaw.

3. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; means for separately swinging into closed position when said tongs are moved upon a pipe to be gripped.

4. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; and means for yieldably urging said latching jaw into closed position.

5. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; means for yieldably urging said latching jaw into closed position; and means for retaining said latch jaw in open position against said yieldable means.

6. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; means for yieldably urging said latching jaw into closed position; means for retaining said latch jaw in open position against said yieldable means; and means for manually disengaging said latching jaw retaining means.

7. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; and means for yieldably urging said latching jaw into closed position.

8. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; means for yieldably urging said latching jaw into closed position; and means for retaining said latch jaw in open position against said yieldable means.

9. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; means for yieldably urging said latching jaw into closed position; and means for retaining said latch jaw in open position against said yieldable means.

10. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; means for yieldably urging said latching jaw into closed position; means for retaining said latch jaw in open position against said yieldable means; means for manually disengaging said latching jaw retaining means; and latch-jaw positioning means for retaining said latch jaw in closed position.

11. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; means for yieldably urging said latching jaw into closed position; yieldably operated means for retaining said latch jaw in open position against said yieldable means; means for manually disengaging said latching jaw retaining means; and latch jaw positioning means for retaining said latch jaw in closed position, said last mentioned means being

- caused to operate by the release of said manual means for disengaging said yieldably operated latch jaw retaining means, when said latch jaw is in closed position.
- 5 12. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; means for yieldably urging said latching jaw into closed position; yieldably operated means for retaining said latch jaw in open position against said yieldable means; means for manually disengaging said latch jaw retaining means; latch jaw positioning means for retaining said latch jaw in closed position.
- 10 13. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; means for yieldably urging said latching jaw into closed position; means for retaining said latch jaw in open position against said yieldable means; means for manually disengaging said latching jaw retaining means; and latch jaw positioning means for retaining said latch jaw in closed position.
- 15 14. In tongs, the combination of a handle; a main jaw provided upon an end of said handle; a free jaw; link means connecting said free jaw to said main jaw; a latch jaw; a latch jaw support for connecting said latch jaw to said main jaw; latching means whereby said latch jaw is latched to said free jaw when said jaws are in closed position; resilient means for holding said free jaw in open position; means whereby said free jaw is swung into closed position when said tongs are moved upon a pipe to be gripped; means for yieldably urging said latching jaw into closed position; yieldably operated means for retaining said latch jaw in open position against said yieldable means; means for manually disengaging said latching jaw retaining means, when said latch jaw is in closed position; and a handle for moving said latch jaw from closed position to open position when said latch jaw positioning means are rendered inoperative by actuating said manual means for disengaging said yieldably operated latch jaw retaining means.
- 20 15. In tongs, the combination of a handle, a main jaw provided upon an end of said handle, a free jaw, link means connecting said free jaw to said main jaw, said free jaw being thereby supported by said main jaw, a latch jaw, a latch jaw support for connecting said latch jaw to said main jaw, and latching means whereby said latch jaw is latched to said free jaw when said jaws are in closed position.
- 25 16. In tongs, the combination of a handle; a main jaw rigidly provided upon an end of said handle; a free jaw, said free jaw being independently movable, link means connecting said free jaw to said main jaw, a latch jaw, a latch jaw support for connecting said latch jaw to said main jaw, latching means whereby said latch jaw is latched to said free jaw when said jaws are in closed position, and resilient means for holding said free jaw in open position independently of said latch jaw.
- 30 17. In testimony whereof, I have hereunto set my hand at Los Angeles, California, this 13th day of November, 1925.
- 35 18. SAMUEL T. SMITH.
